L. K. SNELL,
HYDROCARBON MOTOR,
APPLICATION FILED DEC. 1, 1916.

Patented June 8, 1920.

INVENTOR

LYLE K. SNEED

ATTORNEY

UNITED STATES PATENT OFFICE.

LYLE K. SNELL, OF DETROIT, MICHIGAN, ASSIGNOR TO CADILLAC MOTOR CAR COMPANY, OF DETROIT, MICHIGAN, A CORPORATION OF MICHIGAN.

HYDROCARBON-MOTOR.

1,342,830.

Specification of Letters Patent.

Patented June 8, 1920.

Application filed December 1, 1916. Serial No. 134,513.

To all whom it may concern:

Be it known that I, LYLE K. SNELL, a citizen of the United States, and resident of Detroit, Wayne county, State of Michigan, have invented certain new and useful Improvements in Hydrocarbon-Motors, of which the following is a specification.

This invention relates to hydrocarbon motors, and particularly to carbureting or fuel-mixing devices therefor.

One of the objects of this invention is to provide simple and efficient means for maintaining a pre-determined level of fuel in a carburetor without the disadvantages associated with the use of float valves.

Another object of this invention is to provide a sealed level regulating chamber with means for the prevention of blowing fuel from the chamber when the carburetor "pops back."

Another object of this invention is to provide a more sensitive level-regulating device for a carburetor; my preferred form being shown and described as affected by the combined action of a resilient member (such as a spring) and the relation of atmospheric pressure to the static pressure of the head of fuel within the nozzle of the carburetor.

These, and other objects, will appear from the following description, taken in connection with the drawings which form a part of this specification, and in which:

Figure 1 illustrates a more or less diagrammatic view of a hydrocarbon motor power plant embodying a form of this invention;

Fig. 2 is a vertical sectional view of the carburetor illustrated in Fig. 1; and

Fig. 3 is a modified form of the valve mechanism illustrated in Fig. 2.

Referring to the drawings, 10 illustrates one of a pair of frame side members upon which a hydrocarbon motor 11 of any well-known form, and a fuel tank 12, respectively, may be mounted. An air pump 13 may be mounted and suitably driven at the front end of the motor 11. A conduit 14 is adapted to communicate the pressure generated within the pump 13 to the fuel supply source 12. Another conduit 15 is adapted to feed the fuel from the tank 12 to the carburetor 16 through a regulating device which will be more particularly referred to hereinafter.

The carburetor 16 is adapted to be con-

nected with the motor intake 17 through flanges 18 and connecting bolts 19. The carburetor is illustrated as comprising a fuel nozzle 20, primary air ports 21, and a secondary air port 22. The latter port is adapted to be automatically controlled by a valve 23 pivotally mounted as at 24, and yieldingly closed by a spring 25. The usual throttle valve is illustrated at 26.

The pressure-regulating device, comprises 60 a stationary lower end wall 27, a relatively movable upper end wall 28, and an inherently resilient and flexible corrugated side wall 29 of tubular form. The lower and upper ends of the side wall 29 may be secured to the upper and lower end walls, respectively, as by clamping the tubular wall at 30 and 31, respectively. The wall 27 has a port 32 formed therein and adapted to communicate with the interior of the fuel-feed conduit 15. The end wall 27 also is provided with another port 33, in which may be threaded a stand pipe 34 whose upper end is in communication with the interior 35 of the regulating chamber. The lower 70 end of the stand pipe is in constant communication with the interior of the fuel nozzle 20.

Referring more particularly to Fig. 2, it will be noted that a valve member 37 is arranged in the port 32, and adapted to regulate the area thereof. The upper end of the valve member 37 is connected, by means of a ball and socket joint 38, with a connecting member 39. The member 39 is in turn connected through another ball and socket joint 40, with a rod 41 adjustably mounted as by threads 42 in the diaphragm upper end wall 28. A lock nut 43 maintains the rod 41 and connected parts in adjusted relation.

With the construction and arrangement of parts described, the operation of my invention will be understood as follows:

Means such as the pump 13 will provide sufficient lifting action to cause the fuel to 100 flow from the tank 12 to the interior 35 of the regulating chamber. Prior to the entrance of fuel into this chamber, the corrugated wall 29 will be slightly contracted axially. The fuel will rise in level until 105 the chamber is completely filled, when further flow of fuel through the port 32 will raise the movable end wall 28, thus expanding axially the resilient tubular wall 29 until the valve member 37 is brought 110

against its seat and closing off the communication of the interior of the chamber 35 with the conduit 15. It will of course be understood that as the level of the fuel in the chamber 35 was raised, any air therein would be discharged through the port 34 of the stand pipe to the fuel nozzle 20, thus preventing the creation of an air pocket in the regulating chamber.

10 The valve mechanism is so adjusted that when there is sufficient fuel in the chamber 35 to seat the valve member 37, the level of the fuel in the nozzle 20 will be also maintained at a proper height. Of course 15 as fuel is withdrawn from the nozzle 20 by suction, the diaphragm 28 is automatically lowered by the combined action of the resilient wall 29 and atmospheric pressure on the wall 28 and the valve 37 unseated, permitting the entrance of fuel. On the other hand, if there is any popping back in the carburetor, thus creating a back pressure in the nozzle 20, there will be an increase 20 of pressure in the chamber 35 which will automatically close off its communication 25 with the source of fuel supply.

It will be also understood that in addition to the inherent resilience of the very sensitive tubular corrugated wall 29, the action 30 of the regulating chamber is affected through the diaphragm 28 by the relation of atmospheric pressure to the static pressure of the fuel within the chamber 35. In other words, as the level of the fuel within 35 the chamber 35 decreased, atmospheric pressure tends, in an increasing degree, to move the end wall 28 toward the opposite wall 27 on account of the changing relation of the internal and atmospheric pressures. 40 Thus, I am enabled to use a very light and sensitive spring action in the wall 29.

Referring more particularly to Fig. 3, it will be noted that instead of closing the valve member 37 through the action of the 45 end wall 28, a spring 44 is adapted to perform this function. The valve member 37 is provided with a ball 45 which merely rests against the lower end 46 of the member 39. In this form, the diaphragm positively opens 50 the valve on a downward movement thereof, and permits the spring 44 to close the valve on an upward movement thereof.

While I have described and will specifically claim what I deem to be preferred embodiments of my invention, it will be obvious to those skilled in the art that various changes, modifications, adaptations, and uses may be made without departing from the spirit and scope hereof.

60 Having thus described my invention, what I claim and desire to secure by Letters Patent is:

1. A carburetor comprising a mixing chamber, a fluid fuel chamber having a 65 stand pipe therein, means for supplying

fuel to said mixing chamber from said fuel chamber, and means controlled by the pressure about the exterior wall of said fuel chamber for regulating to a constant pressure the flow of fuel to said mixing chamber 70 from said fuel chamber through said stand pipe.

2. A carburetor comprising a mixing chamber, a compressible fuel supply vessel, and a stand pipe arranged in said vessel and 75 through which fuel is fed to said mixing chamber and having communication with said mixing chamber.

3. A carburetor comprising a mixing chamber, a nozzle arranged in said mixing 80 chamber and connected to a supply pipe having a valve mechanism connected therewith for regulating the flow of fuel therethrough, and an expansible fuel vessel operatively connected with said valve mechanism 85 and having a stand pipe therein through which fuel flows to said mixing chamber.

4. A carburetor comprising a mixing chamber, a nozzle arranged in said mixing 90 chamber and connected to a supply pipe having a valve mechanism connected therewith for regulating the flow of fuel therethrough, an expansible fuel vessel operatively connected with said valve mechanism, and a stand pipe arranged in said fuel vessel and supplying fuel at a constant level 95 to said nozzle.

5. A carburetor comprising a mixing chamber, a nozzle within said mixing chamber and connected to a supply pipe having valve mechanism connected therewith for regulating the flow of fuel therethrough; a fuel supply vessel having a ported stationary end wall and movable end wall, said 105 walls being connected by a flexible corrugated tubular wall and having a stand pipe therein through which fuel flows to said mixing chamber, a valve member adjacent said stationary wall, and a universal connection between said movable wall and said 110 valve member, said movable wall being unconnected with any other movable parts, whereby it may have free lateral movement.

6. A carburetor having a fuel nozzle, a 115 collapsible fuel supply vessel having a stationary end wall, a movable end wall, and a corrugated tubular side wall, said vessel having a valve mechanism and a port in constant communication with the interior of 120 said nozzle, and a connection between said movable end wall and said valve mechanism, whereby a rise in the level of the fuel in said nozzle, above the normal, will cause an upward movement of said latter mentioned 125 wall, to close said valve mechanism.

7. A carburetor having a fuel nozzle, and a source of supply therefor, means connecting said source and said nozzle comprising a fuel level regulator, said regulator com- 130

prising a chamber sealed against communication with the atmosphere and having ports connected with said nozzle and said source, respectively and a stand pipe in said chamber through which fuel flows to the port connected to said nozzle.

5. In a carbureter, a nozzle and means for maintaining a predetermined level of fuel

therein, comprising a vessel having relatively movable end walls connected by a flexible side wall and a port connected with a source of fuel supply and having a stand pipe connecting the interior of said vessel with said nozzle.

10. In testimony whereof I affix my signature. 15
LYLE K. SNELL.
